Nov 14, 1882

UNITED STATES PATENT OFFICE.

JOHN L. POPE, OF CLEVELAND, OHIO.

DESIGN FOR A CARRIAGE-STEP.

SPECIFICATION forming part of Design No. 13,415, dated November 14, 1882.

Application filed August 2, 1882 Term of patent 14 years.

To all whom it may concern:

Be it known that I, JOHN L. POPE, of Cleveland, in the county of Cuyahoga and State of Ohio, have invented and produced a new and original Design for Carriage-Steps, of which the following is a specification, reference being had to the accompanying photographic illustration, forming part thereof.

My present invention relates to a new design for carriage-steps; and it consists, first, in a novel shape or configuration of the sides thereof; and, secondly, in certain features of ornamentation of the top surface of the step, all as will be hereinafter more particularly described and claimed.

In the photographic view which accompanies this specification it will be observed that the four sides *a a a a* of the step are curved or bow-shaped. This, so far as my knowledge extends, is a new configuration, and forms one of the main features of my invention. Heretofore the sides of the step have been made straight, with or without rounding corners. The upper surface or front face of the step is adorned by the employment of two quarterfoils surrounding a central ornamented figure, all formed of

ribbed or raised work. The quarterfoils, which I have marked *b* and *c*, respectively, are oppositely disposed or crossed, and joined at their cusps to the sides *a* of the step, as plainly seen. The inner points, *d*, of the foils are contiguous to the ring *e*, which latter is shown ornamented by four arch-shaped figures whose points approach the center of the step.

Instead of making the plate with openings, as shown, it may be made closed between the foliated work, and yet the ribs would still show the novel pattern of ornamentation intended to be secured.

What I claim as new, and desire to secure by Design Letters Patent, is—

1. A carriage-step having curved sides, substantially as shown.
2. A carriage-step ornamented with two quarterfoils surrounding a central figure, substantially as shown.

In testimony whereof I have hereunto set my hand this 31st day of May, 1882.

JOHN L. POPE.

In presence of—

A. A. POPE,
C. M. COPP.
